PICK-OUT SHIELD FOR POULTRY

John A. Gawiler, Toppenish, Wash.

Application November 5, 1935, Serial No. 48,322

9 Claims. (Cl. 119—143)

This invention relates to pick-out shields for poultry and more especially to that class of shield which is adapted to overlie the rectal opening of the fowl, as illustrated and described in my prior application for Letters Patent of the United States, Ser. No. 588,213, filed January 22, 1932, maturing into Letters Patent No. 2,086,612 of date July 13, 1937.

The present invention is particularly directed to and has for its objects the provision of improvements in the attachment device by means of which the shield is more advantageously applied as well as in the improved design of the shield whereby a more effective protection against pick-outs is obtained.

More particular objects and advantages, together with the foregoing, will become apparent in the course of the following description and in the claims annexed thereto, the invention consisting in the novel construction, adaptation, and combination of parts hereinafter described and claimed.

In the drawing:

Figure 1 is a perspective view representing the body outline of a fowl with the now preferred embodiment of my invention applied thereto.

Fig. 2 is a side elevation of the invention taken to an enlarged scale with a portion of the shield shown in vertical section, a fowl to which the shield is attached being represented in dotted lines.

Fig. 3 is a rear elevation thereof.

Fig. 4 is an enlarged detail side elevation and Fig. 5 a detail rear elevation of one of the pin elements employed in attaching the shield.

Fig. 6 is a transverse horizontal section taken to an enlarged scale on the line 6—6 of Fig. 3.

Fig. 7 is a detail elevation indicating the position of the parts in withdrawing the pin elements from the keeper therefor; and

Fig. 8 is a transverse horizontal section taken on the line 8—8 of Fig. 7.

My patent above had reference to clearly describes the purpose of the pick-out shield and suffice it to say, in general, that the shield is attached at its upper end by means of a pin which is passed through the fatty rump of the fowl lying above the rectal opening, the shield depending from its pin connection to overhang the opening. The shield, indicated in the drawing by the numeral 10, is curvilinear in lower edge elevation and, considered in plan, is of a general triangular shape inclined somewhat to the pelecoid in that the lateral edges leading from the extended wings 55 upwardly to the pin-connecting end 12 are

curved inwardly. A peripheral flange reinforces the shield.

In the structure disclosed in my prior patent, a common safety pin was employed with the pointed strand of the two pin elements being passed horizontally through the fatty rump of the fowl, the companion guard-carrying strand lying under the rump and connecting with the upper end of the shield. The shield itself was formed with its vertical median line disposed approximately rectilinearly and, while the arrangement has operated in a highly satisfactory manner, a disadvantage which the present invention overcomes has been a tendency of the shield to incline rearwardly from its pin connection due to the protrusion of the rectum-forming portion of the fowl's body lying below the hinge.

As best illustrated in Fig. 2, I form the upper extremity or that portion of the shield which lies adjacent the pin-connecting extremity curvilinear so that the median line of the shield at its point of intersection with the lower edge lies in the approximate vertical plane of the hinge, the shield body inclining rearwardly therefrom with the upper curved end extending outwardly beyond the rectal protrusion. Co-active with this improved design of the shield, I have devised an especially advantageous pin arrangement adapted to facilitate the attachment of the shield to and the removal of the shield from the fowl and which additionally operates to obtain a more secure hinge connection in that movement of the pin about the rump-penetrating strand as an axis is prevented.

Referring to said pin, I form the same to a relative U-shape to provide a pair of relatively parallel vertical branch elements 15 connected at their lower ends by a horizontal arm element 16, the arm being hinged in the eye-forming extremity of the shield's upper end and the vertical branches being pointed at their upper tips for passing the same vertically through the fatty rump of the fowl, the branches being of a length to project above the rump and in their exposed ends at opposite sides of each element providing notches 17. Said notches desirably are constituted with a sharp jog at their respective upper limits and are formed by flattening the material under pressure to express the same laterally whereby nodular extensions 18 are provided which lie in the horizontal plane of the notches at each opposite edge of the same.

Adapted for reception over said exposed tips of the branch elements is a keeper formed from a rectangular blank of spring metal bent on its

approximate transverse median line to provide a pair of limbs 21 diverging downwardly with the lower ends of the latter being brought inwardly and upwardly in the provision of companion meeting jaws 22, the blank providing parallel cuts in proximity to the side edges of one of the jaw-forming terminals to form lateral fingers 23 which, as the blank is bent, are disposed to lie horizontally in a plane below that of the jaw 10 whereby the fingers extend over and beyond the longitudinal vertical center line of the keeper and act as stops at each end of the jaws.

In using the shield, the pin branches 15 are passed through the rump of the fowl and the keeper introduced as a guard over the exposed tips, the jaws 20 spreading to admit the branch elements and closing below the horizontal notch shoulders to lock the keeper in position. To remove the keeper, the same is given a quarter 20 turn as indicated in Figs. 7 and 8 to dispose the nodular extensions 18 at right angles to the interstice of the jaws, the extensions 18 spreading the jaws in opposition to the spring characteristic of the keeper to release the pin branches 15.

25 Modifications of the invention will readily appear and it is my intention that the same be limited only as by the scope of the hereto annexed claims.

What I claim, is:—

30 1. In combination with a pick-out shield of a character adapted to be suspended from the fatty rump of a fowl to overlie the rectal opening, a pin member shaped to a relative U to provide laterally disposed parallel arms and a medial portion connecting the arms, said medial portion having a hinge connection with the upper end of the shield and the laterally disposed arms providing pointed extremities for passing the same vertically through the fatty rump of the fowl, and a keeper adapted to engage over the tips of the rump-penetrating arms to guard the points and prevent retraction of the arms from the rump.

45 2. In combination with a pick-out shield of a character adapted to be suspended from the fatty rump of a fowl to overlie the rectal opening, attachment means therefor comprising relatively parallel pin elements hingedly connected to the shield at one end of the same and having their 50 opposite ends pointed for passing the pin elements upwardly through the fatty rump of the fowl at each side of the terminal point of the fowl's back-bone, and means adapted to fit over the protruding points of the pin elements to resist retraction of the pin elements from the rump.

55 3. A clasp appliance comprising a member of spring wire formed to a relative U shape with the side elements having pointed extremities and providing notches below the points, the material 60 along each edge of the notches projecting outwardly to provide nodular extensions, and a keeper adapted to be introduced over said points for guarding the same, said keeper providing spring-closing companion jaws arranged to engage in the notches for locking the keeper against retraction from the pin member, the nodular extensions acting in response to a twisting of the keeper to spread the jaws in dislodging the keeper.

70 4. A clasp appliance comprising a pin element pointed at its extremity and providing oppositely disposed notches in the walls of the element below the point, the material along each edge of the notches projecting outwardly to provide nodular extensions, and a keeper of spring metal 75 formed to a general V-shape in edge elevation

with its free terminals bent inwardly and upwardly toward the apical point of the keeper to provide companion spring-closing jaws arranged to engage in the notches for locking the keeper against dislodgment from the pin element, said nodular extensions acting in response to a twisting of the keeper relative to the pin element to spread the jaws for releasing the jaws from the notches.

5 5. In a keeper for the point of a pin characterized by the provision of oppositely disposed notches below the point, a guard member formed from a strip of spring metal bent on its approximate transverse median line to provide companion limbs projecting in diverging relation from the line of the bend, one of the limbs being terminally provided with parallel longitudinal cuts and the material between said cuts together with the terminal portion of the other limb being bent inwardly and upwardly toward the juncture of the limbs to produce spring-closing jaws, the laterally-disposed fingers lying at each side of the turned-in portion of the first-named limb being turned inwardly to an inclination less than that of the jaw elements to overlie the interstice between said jaw elements and thereby form closures at each end of the interstice, said guard member being adapted for introduction over the point of the pin with the spring-closing jaws engaging in the notches to lock the keeper against retraction from the pin.

10 6. In a keeper for a pin having notches at diametrically opposite sides of its tip portion, a member of spring metal bent to provide companion limbs projecting in diverging relation from the line of the bend, each of said limbs being terminally formed with turned-in portions to provide opposing spring-closing jaws and one of the limbs, at each side of the jaw, providing turned-in finger elements overlying the interstice between the jaws to operate as closures at each end of said interstice, said member being adapted for reception over the tip of the pin to have the spring-closing jaws engage in the notches and thereby lock the pin against retraction.

15 7. In combination with a pick-out shield adapted to be suspended from the fatty rump of a fowl to overlie the rectal opening, a supporting pin therefor of a relative U-shape hingedly coupled by its medial portion to the shield and having its prongs pointed for passing the same upwardly through the fatty rump of the fowl to lie at opposite sides of the rear terminus of the fowl's back-bone.

20 8. In combination with a pick-out shield adapted to be suspended from the fatty rump of a fowl to overlie the rectal opening, a supporting pin therefor formed to a relative U-shape and hingedly coupled by its cross arm to the shield with its prongs arranged to be passed upwardly 25 through the fatty rump of the fowl to lie at opposite sides of the rear terminus of the fowl's back-bone with the tips thereof exposed above the rump, and a keeper operative to engage said protruding tips to operate as a guard for the tips and to resist dislodgment of the pin from the rump.

25 9. In combination with a pick-out shield adapted to be suspended from the fatty rump of a fowl to overlie the rectal opening, means hingedly connected with the shield and arranged to be vertically embedded in said rump from the underside thereof for functionally supporting the shield.
